Inventor,

Leonard Gerhardt

By his Attorney,

Meyers, Cushman & Rao

UNITED STATES PATENT OFFICE.

LEONARD GERHARDT, OF ARLINGTON, MARYLAND, ASSIGNOR TO TIN DECORATING COMPANY OF BALTIMORE, OF BALTIMORE, MARYLAND, A CORPORATION OF NEW JERSEY.

SIFTER-CONTAINER.

1,278,455.

Specification of Letters Patent. Patented Sept. 10, 1918.

Application filed January 14, 1918. Serial No. 211,716.

To all whom it may concern:

Be it known that I, LEONARD GERHARDT, a citizen of the United States, residing at Arlington, in the county of Baltimore and 5 State of Maryland, have invented new and useful Improvements in Sifter-Containers, of which the following is a specification.

This invention relates to sifter containers and has particular application to the construction of the top or cover through which the pulverized or powdered material is adapted to be sifted or shaken.

As it is well known, containers of this general type are employed for holding or 15 dispensing pulverized materials such as talcum or toilet powders and the like, and are usually made of tin or other metal. In some instances it is the practice to make the top or cover of the can with an elevated neck 20 having a perforated top wall which is surmounted with a shiftable, perforated cap plate for permitting the escape of the contents according as the perforations of the cap plate are moved into and out of register with the perforations of the top wall. 25 Such a type of can is relatively expensive to make, however, requiring as it does certain special tools and a number of distinct manufacturing operations, in addition to requiring a relatively large amount of metal.

On the other hand, cans which are devoid of this elevated neck structure are usually complicated and cumbersome in construction, and are difficult to manipulate in opening and closing, and in addition, do not retain the contents properly sealed when the container is closed, but having open seams, cracks and the like, will usually allow the powder to sift through or escape.

Furthermore, the cans of both the above mentioned types with which I am acquainted present another serious disadvantage, and that is that owing to the irregular shapes and forms of the tops or covers and the parts 40 thereof, such as springs, projections, ledges and the like, it is a difficult matter to economically pack and store these cans in boxes or cartons for shipment, but on the contrary considerable space is usually wasted.

In the present instance I have devised a 50 type of container having a sifter top which is devoid of the above mentioned objections

incident to both the neck and neckless type of cans, for in my construction is not only a minimum amount of metal employed, but 55 the number of operations required to make the top are few in comparison with the manufacture of the ordinary sifter container, and furthermore, owing to the construction and location of the parts or cover of my 60 container a number of the latter may be compactly, economically and closely packed in a carton or other receptacle, for storage and shipping purposes.

Another object of my invention is the 65 provision of a sifter top for containers which is so constructed that when closed the contents will be positively and securely sealed against accidental sifting or escaping, as there are no cracks or open joints through 70 which the material can flow.

It is also my purpose to provide an article of this class wherein the can may be conveniently and easily manipulated and opened and closed, the use of but one hand being 75 required for this purpose.

I also aim to provide a container which will embody the desired features of simplicity, efficiency and neatness, and which may be manufactured and marketed at a 80 relatively low cost.

With the above recited objects and others of a similar nature in view my invention consists in the construction, combination and arrangement of parts set forth in and falling within the scope of the appended claims.

In the accompanying drawings:

Figure 1 is a perspective view of a sifter container embodying my invention.

Fig. 2 is a similar view of the top or 90 cover of the can but with the movable closure plate removed.

Fig. 3 is a top plan view.

Fig. 4 is a vertical longitudinal sectional view taken through a portion of the closed 95 container.

In the present instance I have shown my invention as embodied in the form of a talcum powder can which is approximately elliptical, or oval in cross section, but it will 100 of course be understood that such invention is not limited in its useful application to this particular style of container.

Referring now to the accompanying

drawings in detail, the letter A indicates the body of the container and B is the cover or top thereof which is removably seated as usual upon the top bead 1 extending around the body. The top wall 2 of the cover or top B is convex or curved, as is best seen by reference to Fig. 4 and is formed at its central portion with a circular exterior bead 3 which is of such relatively small diameter as to lie within the confines of the marginal edge 4 of the top wall. The portion of the top wall lying within the bead 3 is formed with a series of properly spaced perforations 5, and a central aperture 6. Through this central aperture 6 projects the shank of a rivet or like fastener shown at 7, and by means of which the closure plate C is pivoted on the top wall. This closure plate C comprises a flat approximately circular head 8 having a series of perforations 9 properly spaced so as to be brought into and out of register with the perforations 5 of the top wall of the cover or top B, the circular head 8 of the plate C having a tongue 10 extending therefrom and lying in a substantially horizontal plane, or in the same plane as the head 8. The circular head 8 of the plate is formed with a circular, hollow marginal bead 11 which overlies and works upon the bead 3 of the container top as is clearly shown in Fig. 4, the closure plate being thus guided and confined in its rotary movement. The tongue 10 of the closure plate is also formed with a marginal bead as at 12, and it will be understood that the complete closure plate may be made in one stamping operation and from a single piece of metal. The body of the tongue is provided with a transversely 40 extending segmental slot 13 through which projects the pin or stud 14 projecting up from the top wall 2 of the cover B, this pin or stud forming a stop limiting the swinging movement of the tongue so that the latter may not swing beyond the marginal edge of the top wall 2 in either direction. It is desirable to thus limit the swinging movement of the tongue within the confines of the top wall of the cover in order 50 to obviate the liability of bending or breaking the tongue, which might happen were it to swing beyond the edge of the cover.

It will further be noted, especially by reference to Fig. 4, that while the tongue extends in a substantially horizontal plane the top wall of the cover B underlying the same is sloped downward from the center toward the outward or marginal edge so that a space is formed between the tongue and the top wall. This construction greatly facilitates the operation of the closure cap for the user may grasp the container in one hand and readily grasp the tongue between the thumb and forefinger to shift said

tongue in either direction of its movement, 65 thus the usual difficulty and inconvenience of manipulating the closure plate which occurs when the grasping section thereof lies close to a wall of the container is obviated.

From the above description, taken in connection with the accompanying drawings, the construction and operation of my improved sifting container will be readily understood. It will be noted that I employ but relatively few parts and these of the simplest construction which may be stamped from metal in a relatively few operations, the use of separate springs, necks and the like being dispensed with, while the parts of the container top are so correlated and assembled as to avoid the accidental escape of the powdery contents.

What I claim is:

1. An elliptical sifter top for containers having a convex wall provided with an elevated circular bead, the section of the top wall within the bead having perforations therein, a closure plate having a pivoted circular head having perforations therein adapted to be brought into and out of register with the perforations of the top wall, said head having a hollow, circular marginal bead overlying and working upon the circular bead of the top wall, a tongue extending laterally from said head, and means for limiting the swinging movement of the tongue to prevent said tongue from being projected beyond the side marginal edge portions of the elliptical top.

2. A sifter top for containers having a convex top wall provided with an elevated circular bead at the central portion thereof, the section of the top wall within the bead having perforations formed therein, a closure plate including a pivoted circular head having perforations therein adapted to be brought into and out of register with the perforations of the top wall, said head having a hollow, circular marginal bead overlying and working upon the circular bead of the top wall, said head also having an elongated tongue extending laterally and horizontally therefrom, said tongue having a transversely-extending segmental slot formed therein adjacent the base, and a stud projecting upward from the surface of the top wall and into the slot in the tongue to limit the swinging movement of such tongue.

3. An elliptical sifter top for containers having a convex top wall provided with perforations, a closure plate including a circular head portion pivoted on the top wall and provided with perforations adapted to be moved into and out of register with the perforations of the top wall, said circular head having a tongue extending laterally therefrom and in substantially the same horizontal plane as the circular head to pro-

vide a substantial space between the tongue and the underlying portion of the convex top wall, and which space extends throughout the length of the tongue and gradually increases in width from the base of the tongue toward the edge of the top wall, said tongue having a segmental slot therein adjacent its base, and a stud extending up-

wardly from the convex top wall and projecting into said slot to limit the swinging 10 movement of the tongue and consequently the movement of the circular head.

In testimony whereof I have hereunto set my hand.

LEONARD GERHARDT.
